CLAIM

The ornamental design for a combined electric ceiling fan and light, as shown and described.

DESCRIPTION

FIG. 1 is a bottom and front perspective view of a combined electric ceiling fan and light showing our new design;

FIG. 2 is a front elevational view thereof;

FIG. 3 is a rear elevational view thereof;

FIG. 4 is a top plan view thereof; and,

FIG. 5 is a bottom plan view thereof.

The broken line showing of environmental structure in FIGS. 1-3 and 5 is for illustrative purposes only and forms no part of the claimed design.

FIG. 1

FIG. 2

FIG. 3

FIG. 4

FIG. 5
